US00D981424S

(12) **United States Design Patent** (10) Patent No.: **US D981,424 S**
Kim et al. (45) Date of Patent: **** Mar. 21, 2023**

(54) **STAND FOR MONITOR**

(71) Applicant: **LG ELECTRONICS INC.**, Seoul (KR)

(72) Inventors: **Yeonjin Kim**, Seoul (KR); **Kiyeal Seo**, Seoul (KR); **Daesung Lee**, Seoul (KR); **Yongho Lee**, Seoul (KR); **Hewon Kihl**, Seoul (KR); **Seungyeon Lee**, Seoul (KR)

(73) Assignee: **LG Electronics Inc.**, Seoul (KR)

(**) Term: **15 Years**

(21) Appl. No.: **35/515,002**

(22) Filed: **May 25, 2022**

(80) **Hague Agreement Data**

Int. Filing Date: **May 25, 2022**

Int. Reg. No.: **DM/221309**

Int. Reg. Date: **May 25, 2022**

Int. Reg. Pub. Date: **Aug. 26, 2022**

(30) **Foreign Application Priority Data**

Dec. 23, 2021 (KR) 30-2021-0062132

(51) **LOC (14) Cl.** **14-02**

(52) **U.S. Cl.**

USPC **D14/452**

CPC **F16M 11/2014** (2013.01)

(58) **Field of Classification Search**

(57) **CLAIM**

The ornamental design for a stand for monitor, as shown and described.

DESCRIPTION

1. Stand for monitor

1.1 : Perspective

1.2 : Rear perspective view

1.3 : Front

1.4 : Back

1.5 : Left

1.6 : Right

1.7 : Top

1.8 : Bottom

1.9 : A rear perspective view showing the state in which the rear cable storage cover is separated.

1.10 : A rear perspective view showing the design of reproduction 1.1 combined with the monitor

The broken lines showing of portions of the monitor in reproduction 1.10 are for the purpose of illustrating envi-

(Continued)

ronmental structure that forms no part of the claimed design. The broken lines indicate portions of the article form no part of the claimed design.

1 Claim, 10 Drawing Sheets
